SPRAYING DEVICE

Edward O. Norris, Westport, Conn.

Application March 29, 1946, Serial No. 658,250

4 Claims. (Cl. 299—63)

1

This invention relates generally to spraying apparatus of the centrifugal type wherein a liquid is fed by suitable means to an atomizing distributor, rotating at high speed, which receives, atomizes, and projects the liquid in a finely divided spray, through a suitable opening in the apparatus, against the surface to be sprayed.

The apparatus disclosed in this application is a modification of the spraying device shown and described in my prior Patents Nos. 2,064,125 and 2,086,987, issued December 15, 1936, and July 13, 1937, respectively. This application is directed to the specific construction of the mechanism for supplying the liquid to the rotating atomizing distributor, the general object of the invention being to render the spraying devices disclosed in the aforesaid patents more flexible and to enable the liquid to be supplied thereto from a large receptacle located at a point remote from the apparatus.

Another object of the invention is to provide a portable spraying device which is simple, compact, light and efficient in operation and which is especially adapted for use by relatively unskilled operators.

Another object of the invention is to provide in a device of this character improved means, utilizing vacuum, for supplying the liquid to the atomizing distributor from a remote source.

Other and more limited objects of the invention will be apparent from the following specification and the accompanying drawings forming a part thereof wherein:

Fig. 1 is a partial central vertical section through a portable spraying device constructed in accordance with my invention;

Fig. 2 is a front elevation thereof;

Fig. 3 is a horizontal section taken on the line 3—3 of Fig. 1;

Fig. 4 is a horizontal section taken on the line 4—4 of Fig. 1; and

Fig. 5 is an enlarged detail sectional view through the valve mechanism which controls the supply of liquid to the distributor.

My improved spraying device comprises generally an atomizing distributor which atomizes and ejects a band of spray out through a suitable opening in a case enclosing the distributor. The distributor is rotated by a high speed series type motor and is mounted in the upper end of a suitable case. The lower end of the case constitutes a reservoir into which the liquid is fed by pressure from any suitable source of supply. From this reservoir the liquid is fed by

2

vacuum means to the distributor which atomizes it and ejects a ring or band of atomized spray outwardly from the periphery thereof. Part of this band of atomized spray is projected out through an opening in the case and the balance thereof is intercepted by the case and drains back into the reservoir. The suction feed by which the liquid is fed from the reservoir to the distributor is so constructed and arranged that the feed is operative when the device is held in various positions suited to project a spray at any angle between horizontally outward and vertically upward. Suitable valve means are provided for controlling the supply of liquid to the reservoir and to the distributor. A float valve operates in conjunction with the control valve to restrict the flow of liquid into the reservoir when the liquid approaches a predetermined level therein.

Referring now to the drawings by reference characters the numeral 1 indicates generally a casing which is divided into upper and lower chambers 2 and 3, respectively, by a spider 4. A motor case 5 of a high speed series type motor having an armature shaft 6 is secured to the top 7 of the casing 1. The armature shaft 6 extends down through an aperture in the top 7 of the casing 1 into the upper chamber 2 and is screwed into the hub 8 of an atomizing distributor, generally indicated by the numeral 9. The distributor 9 is disposed within the chamber 2 between the top wall 7 of the casing 1 and the spider 4 which divides the casing 1 into upper and lower chambers 2 and 3. The lower chamber 3 serves as a reservoir for the liquid which is fed under pressure from any suitable source of supply through a flexible hose 10, valve body 11, and tube 12 into the chamber 3. The tube 12, which is suitably fastened to the casing 1, extends upwardly from the valve body 11 along the outside of the casing to the top wall 7 thereof where it is doubled back upon itself and extends down into the chamber 3 along the inner surface of the casing 1 for a predetermined distance. The flow of liquid from the source of supply into the chamber 3 is controlled when the device is upright as in Fig. 1 by a ball valve 13 within the valve body 11. A valve 14 which is disposed within the tube 12 adjacent the open end thereof is controlled by a float 15 which is connected thereto by an arm 16. When the liquid within the chamber 3 approaches a predetermined level the float will close the valve 14 and restrict the flow of liquid into the chamber 3, even though the valve 13 is open.

The valve 14 is provided to keep the chamber 3 from being flooded in the event liquid is being supplied thereto faster than it is being withdrawn therefrom.

From the chamber 3 the liquid is fed by means hereinafter described to the distributor 9, which atomizes and sprays a band of atomized spray outwardly in all directions from the periphery thereof. A portion of this band of atomized spray is projected out through an opening 17 in the wall of the chamber 2 and the balance thereof is intercepted by the walls of the chamber and drains back through openings 18 in the spider 4 into the chamber 3. The circumferential width of the band of spray projected out through the opening 17 is obviously dependent upon the circumferential extent of this opening. A gate 19 by which the extent of the opening 17 may be varied to increase or decrease the width of the band of spray projected therethrough is slidably mounted within the chamber 2 in operative relation to the opening 17. An operating handle 20, by which the gate 19 is moved to vary the extent of the opening 17, is secured to the gate 19 and extends downwardly therefrom along the outer surface of the casing 1.

The distributor 9 includes upper and lower circular plates 21 and 22 which are disposed in spaced relation to each other. A plurality of superimposed ring-shaped discs 23 are mounted between the plates 21 and 22, the plates 21 and 22 and the discs 23 being all secured together in proper relation to each other by studs 24 and spacers 25. The upper plate 21 is formed integrally with the hub 8 which extends downwardly therefrom towards the lower plate 22. The lower plate 22 is formed with a centrally disposed downwardly extending frusto-conical chamber 26 which is closed at its upper larger end by a flexible disc 27 secured to the lower end of the hub 8. The disc 27 which may be made of leather, impregnated cloth, or any other suitable flexible material, acts as a valve, as is hereinafter apparent, which allows liquid to be thrown upwardly and outwardly from the chamber 26, but prevents air being drawn back into the chamber 26. An annular ring of pyramidal-shaped teeth 28 are formed integrally with the lower plate 22 around the upper end of the chamber 26 and extend upwardly from the plate 22 within the ring-shaped discs 23 and terminates slightly above the upper surface of the uppermost disc 23.

A tube 29 which is closed at its lower end and open at its upper end extends upwardly from the bottom of the chamber 3 through the spider 4 and into the frusto-conical chamber 26. The tube 29 is held rigidly in position by the spider 4 and it has two openings 30 and 31 through the wall thereof, the opening 30 being near the bottom thereof and the opening 31 being near the upper end thereof. An open-ended tube 32 communicates with the opening 31 in the tube 29 and extends outwardly and upwardly therefrom, terminating at a point near the inner wall of the chamber 2, slightly below the top wall 7 thereof. A tube 33 closed at its lower end and open at its upper end is rotatably mounted within the tube 29. The tube 33, the outside diameter of which is approximately equal to the inside diameter of the tube 29, extends from the bottom to the top of the tube 29 and has two openings 34 and 35 through the wall thereof. The openings 34 and 35 are offset about 90° with respect to each other and are adapted to register with the openings 30

5 and 31 respectively. Due to their offset relation, the opening 34 will be moved out of register with the opening 30 as the tube 33 is rotated to bring the opening 35 into register with the opening 31, and vice versa. A tube 36, the outside diameter of which is considerably smaller than the inside diameter of the tube 33, extends up through the tube 33 axially thereof so as to provide a passageway between the inner wall of the tube 33 and the outer wall of the tube 36. The tube 36, which is open at its upper end, extends up beyond the upper ends of the tubes 29 and 33 into a recess 37 in the armature shaft 6 and distributor hub 8, which recess is open at its lower end to the chamber 26. The lower end of the tube 36 extends out through the closed ends of the tubes 29 and 33. The tube 36 is fixed to the bottom wall of the tube 33 and is rotatable in the bottom wall of the chamber 3. The tube 36 terminates in a valve casing 38 having a port 39 which vents the tube 36 to the atmosphere. A ball valve 40 within the casing 38 is arranged to close the port 39 when the apparatus is spraying and to open the port 39 when spraying is discontinued. The interior of the tube 36 is connected, above the valve casing 38, to any suitable source of suction by a flexible hose 41. A lever 42 secured to the tube 36 exteriorly of the casing 1 is provided to rotate the tubes 36 and 33 to bring the openings 34 and 35 into or out of register with the openings 30 and 31 as desired. The device is designed to operate or spray at any angle between horizontally outward and vertically upward. When spraying horizontally or at any angle between the horizontal and approximately 45° upwardly, the openings 39 and 34 are brought into register by turning the tube 33 by the lever 42. At greater angles between the horizontal and the vertical, the openings 31 and 35 are brought into register which moves the openings 30 and 34 out of register with each other.

45 The flow of liquid from the source of supply into the chamber 3 and from the chamber 3 to the distributor 9 is controlled and regulated by a lever 43 pivoted at 44 to a bracket 45 secured to the lower end of the casing 1. The lower end of the lever 43 is bifurcated as indicated at 46 and straddles the projecting end of a rod 47 which is slidably mounted in the valve body 11. The ends of the rod 47 have heads 48 and 49 thereon. A spring 50 within the valve body 11 bearing against the head 48 normally holds the ball valve 40 in position to close a passageway 51 through which liquid flows from the flexible hose 10 into the tube 12.

55 The ball valve 40 is secured to the upper end of a stem 52 which extends out from the valve casing 38 through the port 39 and is secured at its lower end to a spring arm 53 secured to the lever 43. When the lever 43 is released as in Figs. 1 and 5 the spring arm 53 holds the ball valve 40 away from the port 39 so that the tube 36 is vented to the atmosphere. The ball valve 40 closes the port 39 when the lever 43 is actuated for spraying.

Operation

In operation the operator holds and manipulates the device by the reduced lower end of the casing 1. Assuming that the device is to be operated at some angle between the horizontal and an angle of 45° upwardly, the openings 30 and 34 are brought into register. The upper end of the lever 43 is then moved towards the casing 1

which first closes the port 39 and then opens the passageway 51 allowing liquid to flow into the chamber 3. After the port 39 has been closed, air will be exhausted from the tubes 33 and 36 and the frusto-conical chamber 26 in the distributor 9, creating a partial vacuum therein. This will cause liquid to flow from the chamber 3 through the registering openings 30 and 34 and up through the tube 33 around the tube 36 and into the frusto-conical chamber 26 in the distributor 9 which is being rotated at approximately 12,000 revolutions per minute. Centrifugal action will cause the liquid to ride up the inclined wall of the chamber 26 and onto the teeth 28 from which it will be thrown onto the ring-shaped discs 23. The discs 23 will atomize and spray the liquid tangentially outward from the periphery of the discs in a ring or band which completely surrounds the distributor. A portion of this ring or band of atomized liquid will be projected out through the opening 17 and the balance thereof will be intercepted by the wall of the chamber 2, surrounding the distributor, and will drain back into the chamber 3. The centrifugal action upon the flexible disc 27 will keep the outer free edge of the disc 27 in engagement with the film of liquid flowing up the inclined surface of the chamber 26 and thus prevent any air being drawn back into the chamber 26 and tube 33 which would impair the vacuum therein. As soon as the lever 43 is released, the passageway 51 is closed and the port 39 is opened through the action of the spring 50. The closing of the passageway 51 will stop the flow of liquid into the chamber 3, and the opening of the port 39 will break the vacuum in the tube 33 and chamber 26 stopping the flow of liquid from the chamber 3 to the distributor.

When the device is used at an angle between 45° and 90° upwardly from a horizontal plane, the openings 31 and 35 are brought into register and then liquid will flow through the tube 32 into the tube 33 and chamber 26 from where it will be distributed as previously described.

As previously stated, the width of the band of spray projected out through the opening 17 is dependent upon the extent of this opening. As the opening 17 is restricted by adjusting the gate 19 to narrow the band of projected spray, the flow of liquid into the chamber 3 can be proportionately reduced. In order to automatically reduce the rate of flow of liquid into the chamber 3 as the extent of the opening 17 is reduced, I have provided cooperating means between the gate 19 and the control lever 43 for accomplishing this purpose. This means consists of a cam 54 secured to the lower end of the arm 28 by which the gate 19 is adjusted. The cam 54 is disposed within the path of movement of the upper end of the lever 43 and is operative to limit the movement of the lever 43 and rod 47 when opening the passageway 51. The cam 54 is so arranged and constructed that the distance the lever 43 can be moved to open the passageway 51 is proportionately reduced as the gate 19 is adjusted to reduce the extent of the opening 17. This feature per se is no part of the present invention as it is shown and claimed in my co-pending application Serial No. 658,249, filed March 29, 1946.

The apparatus is particularly adapted for paint spraying. It is obvious however that the apparatus can be used equally well for atomizing and spraying other liquid, such as a liquid disinfectant.

It is to be understood that my invention is not

limited to the specific construction shown and described herein as various modifications can be made therein within the scope of the appended claims.

5 What is claimed is:

1. In a spraying apparatus, the combination of a casing having a spray opening therein, a centrifugal distributor positioned to project a band of atomized liquid out through said spray opening, a liquid reservoir in said casing below said distributor, a tube extending upwardly from said reservoir to said distributor, a suction pipe communicating with the top of said tube to create a vacuum in said tube and having a port normally venting said tube to the atmosphere, a valve to close said port, a conduit through which liquid is supplied to said reservoir, a supply valve in said conduit for controlling the flow of liquid through said conduit, and a control lever mounted on said casing having linkages connected to first close said port valve to create a suction in said tube and then to open said supply valve to allow liquid to flow through said conduit into said reservoir in response to progressive positions of

25 said lever.

2. In a spraying apparatus, the combination of a casing having a spray opening, a centrifugal distributor in said casing having means to atomize and spray liquid outwardly from the periphery thereof and positioned to project said spray through said spray opening, a liquid reservoir in said casing below said distributor, means for supplying liquid to said reservoir, a tube extending upwardly from said reservoir to said distributor, suction means communicating with the top of said tube to cause the liquid to flow upwardly in said tube to said distributor, a pair of vertically spaced ports in said tube communicating with said reservoir, valves for opening and closing said ports, and manual control linkages connected to selectively actuate said valves.

3. A spraying apparatus, as set forth in claim 2, in which said reservoir is shaped and positioned to receive liquid by gravity from said distributor when said apparatus is in a vertical position and also when said apparatus is in a horizontal position, one of said ports being positioned to communicate with the liquid in said reservoir when said apparatus is in vertical position, the other of said ports having associated therewith means communicating with the liquid in said reservoir when said apparatus is in horizontal position.

4. In a spraying apparatus, the combination of a casing having a spray opening, a centrifugal distributor in said casing having means to atomize and spray a band of atomized liquid outwardly from the periphery thereof and positioned to project said band of spray through said spray opening, a liquid reservoir in said casing shaped and positioned to receive liquid from said distributor by gravity when said apparatus is in either vertical or horizontal position, means for supplying liquid to said reservoir, a stationary tube having a lower closed end disposed in said reservoir and an open discharge end in said distributor, suction means connected to apply suction to the upper end of said tube for feeding the liquid upwardly therein, a pair of axially spaced aligned openings through the wall of said stationary tube positioned respectively to receive liquid from said reservoir when said apparatus is in vertical and horizontal positions respectively, a rotatable tube

disposed within said stationary tube and having a wall disposed to close said openings, a pair of axially spaced radially offset openings through the wall of said rotatable tube positioned to register selectively with said first openings, and means for rotating said rotatable tube to selectively bring the openings in said rotatable tube into register with the openings in said stationary tube.
